(57) **CLAIM**

I claim the ornamental design for the waxing and polishing device, as shown and described.

DESCRIPTION

FIG. 1 is a top perspective view of a waxing and polishing device, the right side view of which is a mirror image; FIG. 2 is a front view of the waxing and polishing device; FIG. 3 is a left side view of the waxing and polishing device, the right side view of which is a mirror image; FIG. 4 is a rear view of the waxing and polishing device; and,

FIG. 5 is a bottom plan view of the waxing and polishing device.

The broken line showing of a power cord is for illustrative purposes only and forms no part of the claimed design.
